CAN OPENING AND CONTENTS DISPENSING
DEVICE

Harry E. Kuehn, Albany, N. Y.

Application November 26, 1952, Serial No. 322,738

3 Claims. (Cl. 222—85)

1

My invention relates to can openers and particularly to improvements in the can opener and dispenser disclosed in my U. S. Letters Patent No. 2,558,541, granted March 11, 1952.

A common domestic practice in opening tin cans containing fluids, such as milk, fruit juices, syrups and the like, is merely to punch two, diametrically opposed holes in the top of the can. One of these holes is used to dispense the fluid while the other functions to admit air into the can. This method is at best inadequate, messy, and highly unsanitary. The liquids being dispensed have a tendency to spill over the side of the can, and also to collect on the top and solidify, thereby clogging the dispensing hole.

The principal object of my invention is to provide an improvement in the device disclosed in my Letters Patent aforesaid, whereby leakage of the can contents between the opening and dispensing device and the top of the can is prevented. A further object is to provide a device of this character which may be readily taken apart so that it may be maintained thoroughly clean.

I accomplish these objects by means of the novel combination and arrangement of elements described below and illustrated in the accompanying drawing in which—

Fig. 1 is a perspective view of a tin can with my device locked on the top thereof;

Fig. 2 is an exploded, enlarged, perspective view of my device;

Fig. 3 is a fragmentary, enlarged front elevation view of my device positioned on top of a can;

Figs. 4 and 5 are enlarged, fragmentary, sectional views in the plane 5—5 of Fig. 1, showing the means for locking my device to a can in two different positions;

Fig. 6 is a fragmentary, enlarged section of Fig. 1 in the plane 6—6; and

Fig. 7 is a fragmentary, sectional view of Fig. 6 in the broken plane 7—7.

Referring to the drawing—

My device comprises a flat, elongated element 1, which forms the main structural member of the device. Turned down at the front end of this element are two flat hooks 2, each of which is adapted to engage the underneath part of the rim of a tin can 3. Centrally-disposed between these two hook portions and extending a substantial distance beyond the hooked end of the element 1, is a spout 4 having a concave cross section. The spout 4 extends rearwardly and merges with the struck out portion 5 which has a de-

2

pending, pointed, sharpened end 6. The lateral edges of the element 1 which extend from the front thereof to a zone slightly beyond the struck out portion 5 are bent upwardly and outwardly at about a 45° angle to the plane of the flat element 1 as shown at 7. Adapted to slide on these edges and fit snugly thereon, is a cover 8 having an opening 9 in the front thereof which straddles the spout 4. Adjacent the rear end of the element 1 is the means for locking the device to the can and which comprises a triangular blade 10 which is riveted or otherwise secured to the shaft 11, which is rotatably mounted in the element 1. Washers 12 and 13 secured to the shaft 11 on either side of the element 1, prevent vertical movement of the shaft 11 and maintain at least the upper corners of the blade 10 in spaced relation to the lower washer. At the top of the shaft 11 and fastened at right angles thereto, is a handle 14, by means of which the blade and shaft may be turned. The edges of the blade 10 are sharpened and the width at the top thereof exceeds the maximum thickness of the blade and shaft.

The foregoing structure is substantially that illustrated in my Letters Patent aforesaid and it will be apparent, that, since the rear of the element 1 is slightly above the top of the can 3, due to the presence of the washer 13 (see Figs. 4 and 5) and the front end of the element 1 rests on the rim of the can, there is a space between the bottom of the element 1 and the top of the can. Because of this space, unless the can is tilted carefully to pour the contents from the spout 4, the contents may flow under the element 1 over the top of the can. In order to prevent this, I have provided a bifurcated element, best shown at 15 in Fig. 2, which has a depending sleeve 16 and a rearwardly extending top flange 17 conforming to the tapering or pointed portion of the opening 18 in the element 1. The element 15 also has a continuous groove 19 extending around the outer side thereof adjacent the top, as shown in Figs. 2, 6 and 7. The element 15 at the top thereof is thus designed to fit closely within the opening formed in the element 1 by striking down the portion 5. In order to maintain the element 15 in cooperation with the element 1 so that it forms, with the struck down portion 5, a laterally enclosed passage between the interior of the can 3 and the spout 4, I have provided notches 20, one only of which is shown in Fig. 2, in the opposite edges of the struck down portion 5 just below the bottom of the element 1. These notches are adapted to re-

ceive the branches of the bifurcated element 21 which is pushed into and through the grooves 19. In order readily to retract the element 21 to detach the element 15 from the element 1 for cleaning, I have provided the element 21 at the end thereof with a depending portion 22.

From the foregoing, it will be apparent that I have provided my can opening and contents dispensing device with means forming a laterally enclosed passage for the flow of the contents of the can 3 into the spout 4.

While I have described my invention in its preferred embodiment, it is to be understood that the element 15 may, if desired, be permanently soldered or otherwise secured to the element 1, thus dispensing with the holding element 21.

What I claim is—

1. A device adapted for opening and dispensing the contents of cans having an end rim projecting slightly beyond the side thereof; said device comprising a flat, elongated, metal element adapted to lie on top of said can; said element having laterally spaced, depending hooks at one end thereof adapted to engage the under part of said rim, an opening therein adjacent said end formed by striking downwardly a centrally disposed portion thereof; said struck down portion being pointed at its lower end adapting it to penetrate the top of said can, and the portion of said element between said hooks being depressed to form a shallow discharge trough extending from a point beyond said hooks to and merging with said struck down portion; means

for locking said device to the top of said can comprising a flat, pointed blade rotatably mounted in said element adapted to be forced through the top of said can and having a handle thereon for turning said blade and locking said device to said can; and a bifurcated element having a depending sleeve adapted to fit closely in the opening formed in said can by said struck down portion, and cooperating with said struck down portion to form a laterally enclosed passage between the interior of said can and said trough.

2. The structure set forth in claim 1 together with means detachably securing said bifurcated element to said flat element.

3. The structure set forth in claim 1 in which said bifurcated element is provided at the top thereof with a flange portion adapted to fit closely within the pointed portion of the opening formed in said flat element by striking down said centrally disposed portion thereof, and with grooves in the opposite sides thereof adjacent the top; and a second, bifurcated element slidably fitted in said grooves and cooperating with said flat element for detachably securing said first mentioned bifurcated element to said flat element.

HARRY E. KUEHN.
